UNITED STATES PATENT OFFICE.

PAUL A. CHAMBERLAIN, OF CHICAGO, ILLINOIS, ASSIGNOR TO MOHAWK CORPORATION OF ILLINOIS, OF CHICAGO, ILLINOIS, A CORPORATION OF ILLINOIS.

RADIO APPARATUS AND CURRENT-CONTROL DEVICE THEREFOR.

Application filed December 4, 1926. Serial No. 152,682.

This invention relates to improvements in radio apparatus, and more particularly to radio receiving sets, and has for its principal object to provide an improved apparatus of the class described wherein the main control devices, as for example the tuning knob and the filament switch, may be conveniently and compactly arranged on the panel.

10 A further object of the invention is to provide a new and improved form of filament switch, as will hereinafter more fully appear.

The invention may best be understood by 15 reference to the accompanying drawing, in which—

Figure 1 is a fragmentary sectional view 20 of a tuning condenser in mounted position on a radio panel and with a filament switch combined therewith, in accordance with my invention.

Figure 2 is a detail view of the filament switch at the inner end of the condenser shaft.

25 Figure 3 is a plan view of the switch shown in Figure 2.

Referring now to details shown in the drawings, I have provided a tuning device indicated generally at 10. In the form 30 shown, said tuning device consists of a multiple unit condenser including end frame members 11—11 and a rotor shaft 12 having a plurality of rotor units 13—13 spaced longitudinally thereof, each of said 35 rotor units comprising a set of parallel plates 14—14 adapted to be interleaved with coacting stator plates (not shown) in a well known manner. The multiple unit condenser herein illustrated, is especially adapted 40 for use with a single control receiving set wherein a plurality of radio-frequency amplification stages are employed, all being tuned by rotation of the single rotor shaft 12. It will be understood, however, that 45 my invention may be utilized in connection with a single unit condenser, if desired, the multiple unit shown being utilized mainly to illustrate the possibilities of reducing the control devices of well known radio receiving sets to a minimum, and disposing these control members in the most advantageous 50 relationship on the radio panel.

As shown herein, the rotor shaft 12 consists of a sleeve 12^a to which the rotor plates

14—14 are secured, and an inner sleeve 15 55 which projects forwardly through a suitable bearing nut 16 on the front frame member 11, and has suitable bearing means at its rear end, as for instance, by a hollow sleeve 17 threaded in the rear frame member 60 and forming a cupped bearing 18 for said inner shaft 15, as clearly shown in Figure 1. The hollow sleeve 17 is adjustable longitudinally by threading the same in the rear frame member 11 and is provided with a lock nut 19 engaging the outer face of said member for holding said sleeve 65 in various positions of adjustment. This sleeve 17 also carries part of the filament switch thereon, as will hereinafter more 70 fully appear.

Control means for the condenser rotor shaft 12 comprises a disk or dial 20 mounted on the outer end of sleeve 15 and suitably secured thereto as by means of a set 75 screw 21. In the form shown, the dial 20 is mounted in a recess 22 formed in a panel 23. The usual dial markings are provided on the outer face 24 of the dial 20 and are visible through an aperture 25 formed in an 80 escutcheon plate 26 which is mounted on the outer front side of the panel 23 and forms a cover for the aperture 22 in which the dial 20 is mounted. The dial is controlled by means of a knob 29 carried on a 85 shaft 30 disposed eccentrically of the indicating dial 20. In the form shown, the shaft 30 is journaled in a bearing 31 carried by the escutcheon plate 26 and is provided with an enlarged roller portion 32 which 90 frictionally engages a ring member 33 carried on the periphery of dial 20. In the form shown herein, the friction ring 33 is made of rubber or its equivalent. A flexible spring 34 is mounted on the panel beneath the bearing portion 32 of shaft 30 in position to maintain said bearing portion or roller in frictional engagement with the bearing ring 33 on dial 20. It will thus 95 be seen that very fine tuning adjustment 100 may be provided for the dial 20 through the offset tuning knob 29.

Referring now to the switch mechanism utilized in connection with the condenser above described, details of the switch are 105 shown in Figures 2 and 3 from which it will be seen that the sleeve member 17 at the rear end of the condenser is provided with a

supporting piece 40, preferably of insulating material. This piece is suitably secured on the outer surface of sleeve 17, as shown in Figures 1 and 3, and forms a support for a pair of spring contact members 41-41 secured thereto by suitable means, such as rivets 42-42. These spring contact members project outwardly or rearwardly in position to be engaged under tension by a switch member mounted on the rear end of a shaft 45. This switch member includes two main parts, the inner part consisting of a rectangularly shaped metallic plate 46 and the outer part, an overlapping rectangularly shaped insulating piece 47. As seen in Figure 2, the arrangement is such that the insulating piece is wider in one direction than the metallic piece 46 so that when the switch shaft 45 is turned into the position shown in this figure, the spring contacts 41-41 engage only the sides of the insulating piece 47, and the circuit will be broken. The metallic piece 46 has opposite sides projecting above and below said insulator piece as shown in this figure, however, so that when the shaft 45 is turned at an angle of 90° from that shown in Figure 2, the projecting margins of metallic piece 46 is then engaged with the terminal members 41-41 to bridge the circuit, as shown in Figure 3. The metallic piece 46 is preferably provided with a pair of projections 46a-46a extending from opposite corners thereof so as to limit the movement of the switch shaft to two positions, namely, "on" and "off". The terminal contacts 41-41 are provided with suitable conductors 48-48 connected in series in the filament circuit (not shown) in any suitable manner so as to provide the desired control thereof. In the form shown, the condenser is of the grounded rotor type in which the rotor is electrically common with the end plates 11, so that it is possible to connect one of the terminal conductors 48 directly to the adjacent end plate 11, as shown in Figure 3.

As seen in Figure 1, the control shaft 45 extends coaxially through the entire length of the condenser shaft and has its front end 50 extending through and projecting beyond the escutcheon plate 26. A control knob 51 is suitably secured to this projecting end of the switch shaft 45 in position to be readily manipulated in the usual manner.

The construction above described affords an extremely simple form of switch mechanism which may be incorporated as a part of the main tuning condenser and form therewith a most compact structure capable of being readily assembled as a unitary structure. The main tuning knob 29 is carried by the escutcheon plate 26 but may also be readily assembled with the associated

tuning dial 20 of the condenser in a most simple and economical manner. 65

I claim as my invention:

1. In radio apparatus, the combination of a control panel, a rotative tuning unit including a frame and a rotor shaft, a dial for said rotor shaft visible from the exterior of said panel, a current control switch mounted on said frame including a control shaft extending coaxially through said rotor shaft, manual control means for said switch control shaft in front of said dial, and a control knob for said rotor shaft disposed eccentrically thereof and operatively connected with the latter. 75

2. In radio apparatus, the combination of a panel, a rotative tuning unit mounted on said panel and including a frame and a rotor shaft, the latter extending through said panel and having an indicating dial thereon, an escutcheon plate on the front of said panel having an aperture therethrough registering with the periphery of said indicating dial, a current control switch mounted on the end of said frame opposite said panel including a control shaft extending coaxially through said rotor shaft, and projecting through said escutcheon plate, a control knob on the front end of said switch control shaft, and a control knob for said rotor shaft journaled in said escutcheon plate eccentrically of said rotor shaft and operatively connected with the latter. 85

3. In radio apparatus, the combination of a rotative tuning unit including a frame, a rotor shaft, and a rotor shaft bearing on one end of said frame, a current control switch mounted on said rotor shaft bearing outside of said frame, a control shaft for said switch extending coaxially through said rotor shaft bearing and rotor shaft, and independent switch and rotor control means both disposed at the opposite end of said frame. 100

4. In radio apparatus, the combination of a rotative tuning unit including a frame, a rotor shaft and a rotor shaft bearing on one end of said frame, a current control switch mounted on said rotor shaft bearing outside of said frame including an insulating piece carried by said bearing and having a pair of oppositely disposed spring contact members projecting rearwardly therefrom, and a rotatable switch member interposed between said contact members, a control shaft for said switch member extending coaxially through said rotor shaft bearing and rotor shaft, and independent switch and rotor control means both disposed at the opposite end of said frame. 115

Signed at Chicago, Ill., this 2nd day of Dec., 1926.

PAUL A. CHAMBERLAIN.
